(57) **CLAIM**

The ornamental design for a folded multipurpose tool, as shown and described.

DESCRIPTION

FIG. 1 is an isometric view from the upper right front of a folded multipurpose tool showing my new design;

FIG. 2 is a right side elevational view of the folded multipurpose tool shown in FIG. 1, the left side elevational view thereof being a mirror image of this view;

FIG. 3 is a top plan view of the folded multipurpose tool shown in FIGS. 1 and 2, the bottom plan view thereof being a mirror image of this view;

FIG. 4 is a rear end elevational view of the folded multipurpose tool shown in FIGS. 1-3;

FIG. 5 is a front end elevational view thereof.

FIG. 6 is an isometric view similar to that of FIG. 1 of the folded multipurpose tool shown in FIGS. 1-5, wherein the broken-line depiction of rivet heads is included merely for illustrative purposes and forms no part of the claimed design.
